UNITED STATES PATENT OFFICE.

KICHISABURO HASHIMOTO, OF NEW YORK, N. Y.

ILLUSION DEVICE.

1,137,756.

Specification of Letters Patent.

Patented May 4, 1915.

Application filed September 28, 1912. Serial No. 722,793.

To all whom it may concern:

Be it known that I, KICHISABURO HASHIMOTO, a subject of the Emperor of Japan, and resident of the borough of Brooklyn, 5 county of Kings, city and State of New York, have invented certain new and useful Improvements in Illusion Devices, of which the following is a specification.

Like all devices of this nature, this illusion is intended to deceive the eye of the observer by combining a plurality of operations in rapid succession. It is a trick that though simple in itself becomes mysterious only because the eye cannot follow all of 15 the operator's actions with the rapidity with which they are made.

I employ an ordinary fan one that may be used in the manner that a fan is usually used to disturb the air surrounding a person, and although I prefer that the fan should be wholly closed when the trick is performed this is not absolutely necessary, as the portions of the fan necessary in the 20 operation of the device are secured together so that they cannot be opened even when the fan is fully spread.

The details of the construction of the fan and the method for performing the trick will be fully set forth as the specification progresses.

The following is what I consider the best means of carrying out this invention.

The accompanying drawings form a part of this specification, in which:

35 Figure 1 shows in elevation the fan closed, the dotted lines show the arrangement of the interior mechanisms. Fig. 2 shows the device in central longitudinal section, this figure is enlarged and slightly distorted so as to accentuate the operable mechanisms. Fig. 3 shows in plan a second coin useful in 40 performing this illusion.

Similar reference numerals indicate like parts in all the figures where they appear.

45 In this device I employ an ordinary folding fan having sticks 1 and 2, parallel and vertically arranged and a plurality of thinner and lighter sticks 3, arranged between the main sticks or ribs 1 and 2. Between the 50 main sticks or ribs 1 and 2 a plurality of sheets of thin paper 4 are secured and usually in such a manner that the lighter sticks or ribs 3 are held at predetermined distances

apart by being secured between this plurality of sheets of paper.

55 The fan is creased as shown at 5 so that when it is closed it will fall into place occupying a small space. It will be seen then from this description that no change is necessary in the general construction of the 60 fan.

Low down in one of the outer and stronger ribs of the fan I provide an elongated perforation 6 through the rib and in line with this perforation though between the rib 1 65 and the paper secured thereon, and the next succeeding fold of the fan 7 I arrange a stiff though thin wire 8, bent at right angles at 9 so as to produce an extension 10, which will protrude through the perforation 6. 70 Secured to the upper end of the wire or rod 8 is a coin, medal or disk 11 which is arranged for a free reciprocation between the member 1 and the next succeeding fold 7. The length of the slot 6 must nearly equal 75 the diameter of the coin 11, and the parts must be so arranged that when the projection 10 is moved downward until it reaches the lower end of the slot 6, the coin 11 will entirely disappear between the folds of the 80 fan as indicated in dotted lines at 12 in Fig. 1. An upward reciprocation of the projection 10 will project the coin almost wholly above the upper edge of the fan as shown at 13, in Fig. 1.

85 I provide a second coin 14 as shown in Fig. 3, this coin is similar in all respects to the coin 11, except that it is not attached to any part of the fan. In performing this trick the projection 10 is depressed thus 90 obscuring the coin 11 and the fan is exhibited open in use as an ordinary fan, the coin 14 may also be exhibited loose and the operator announces that he will place the loose coin upon the top of the fan, he passes his 95 hand over the fan and while palming the coin 14 projects the coin 11. He then apparently removes the coin from the top of the fan by passing his hand once more over the fan at the same time depressing the projection 10 and thereby the coin 11. The upper end of the fan may be then inserted into a pocket, behind a person's head or in any other place where the observer cannot 100 watch it and the coin 11 caused to appear, 105 although by this series of actions the ob-

server led to believe that it is the coin 14 that has been restored to the top of the fan. The operator may then pass his hand over the top of the fan at the same time depressing the coin 11, he exhibits the coin 14 and spreads the fan to show that no substitution of the fan has been made.

To add to the mystery surrounding this illusion the coin 14 may be omitted and 10 a current coin being secured to the wire 8, a coin of the same denomination may be borrowed from the observer, who will apparently see his own coin appear and disappear at the will of the operator.

15 It is obvious that other modifications may be made within the scope of the appended claim without departing from the principle or sacrificing the advantages of this invention.

Copies of this patent may be obtained for five cents each, by addressing the "Commissioner of Patents Washington, D. C."

What I claim and desire to secure by Let- 20
ters Patent is:—

An illusion device having in combination a foldable member, a plurality of supports therefor one of said supports being provided with a slot, a rod extending parallel and 25 adjacent to said slotted support and having its lower end projecting into said slot and a solid disk attached to the other end of said rod and adapted thereby to be retrieved into and between certain folds of said foldable 30 member as herein specified.

Signed at New York city, in the county of New York and State of New York, this 14th day of Sept., 1912.

KICHISABURO HASHIMOTO.
